POINT AND SIGNAL CONTROL SYSTEM FOR
RAILWAYS AND THE LIKE

Charles Francis Dickson Venning, London, England, assignor, by mesne assignments, to The Union Switch and Signal Company, Swissvale, Pa., a corporation of Pennsylvania

Application November 22, 1940, Serial No. 366,777
In Great Britain January 14, 1939

8 Claims. (Cl. 246—160)

This invention relates to point and signal control systems for railways and the like, and has for its object to provide certain improvements in systems of this character relating to the control of approach locking of a route controlled by a signal or signals.

This application is a continuation in part of my copending application for Letters Patent of the United States, Serial No. 315,549, filed January 25, 1940, for Point and signal control systems for railways and the like.

It is usual to provide arrangements for approach locking which prevents points, that is, track switches, in a route governed by a signal from being operated from one position to the other if a train or vehicle is present in the section of the track leading to the signal concerned, and the signal is, or has been, cleared and the associated signal or route lever or control equivalent has been placed in the clear position. In cases in which this signal is arranged to be automatically set to "danger" by the passing of a train or vehicle into the section controlling the signal, the approach locking may be controlled by a relay which is energized so long as the signal is at "danger" and when thus energized effects the release of the approach locking. The re-setting of the signal to "clear" after a train or vehicle has left the section controlling the signal, is arranged to restore the approach locking conditions which become effective upon the approach of a train or vehicle as above described. Approach locking control schemes of this type are shown and described in United States Patent No. 1,822-218, granted September 8, 1931, to Arthur P. Jackel, for Railway traffic controlling apparatus, and in United States Patent No. 2,211,522, granted August 13, 1940, to Lester E. Spray, for Multiple control apparatus.

In order to prevent the signal from being automatically re-set to "clear" after the passage of a train as above described, the automatic setting of the signal to "danger" is effected by a disengaging relay which is de-energized when the train enters the section controlling the signal and can only be re-energized when the signal or route lever/or its equivalent is manually operated to the "danger" or "normal" position temporarily after the passage of the train. Relays t_2 and t_3 , shown in Fig. 5 of the Spray patent already referred to, are controlled in this manner. Another United States patent, No. 2,106,990, granted February 1, 1938, to Harry C. Vantassel, for Remote control systems, shows a relay TS which is also controlled in this manner. In such cases

it is usual for the approach locking to be released by the energization of a further relay, the pick-up circuit of which is only energized when the signal is at "danger" and either the approach section is unoccupied or the disengaging relay is de-energized, this further relay being provided with a stick circuit completed so long as the signal remains at "danger." The disengaging relay de-energized is employed in this approach locking circuit to prevent the continuance of the approach locking by a second train or vehicle approaching the signal at "danger," after the first train or vehicle has passed out of the section governed by the signal and the signal or route lever or equivalent has not been restored to its normal position before the second train or vehicle has occupied the approach locking track circuits. Relay RMR, shown in the Vantassel patent already referred to, is controlled in this way by relay TS for releasing the approach locking. In the Spray patent already mentioned, relay P_1 shown in Fig. 1 could be controlled in this way by substituting a contact of relay t_2 for contact t_2^{12} .

25 In the case, however, of a signal provided with approach locking and being controlled independently of track circuits, that is to say, being set to its "danger" or "clear" position otherwise than automatically by the passage of a train or vehicle, the relay arrangement above described cannot be employed since a disengaging relay, if utilized, might become permanently de-energized owing to a broken wire for example, and the approach locking become permanently released while the signal is in the "clear" as well as the "danger" position. If, for instance, signal S_1a shown in the Spray patent were controlled to remain in the clear position even though relay t_2 , if a contact of this relay were substituted for contact t_2^{12} , remains de-energized, relay P_1 would remain energized even though signal S_1a were clear and a train were approaching this signal in section a —A while relay t_2 is falsely de-energized due to a broken wire in its pick-up circuit.

30 According to the present invention in which the signal provided with approach locking is controlled independently of track circuits, an approach locking release relay is provided which is arranged when in its energized position to effect the release of the approach locking providing that the signal is at "danger," this relay being normally de-energized when the signal or route lever or its equivalent is in the normal position for no traffic along the route and only re-energized when the signal or route lever or its equivalent is in the

reverse position and a selected track circuit beyond the signal is occupied.

Any failure in the circuits for the relay IANS will thus prevent the approach locking from being released, thereby ensuring safety in operation.

The invention is particularly applicable to systems in which points or track switches are arranged to be controlled by route setting and locking relays comprising normal and reverse solenoids, which in turn cause to operate point or switch setting and locking relays to the required positions to effect the operation of the track points or switches in the route to which a route setting and locking relay applies and which relay remains locked in the position to which it was last set until the opposite solenoid is energized.

A relay of this type, designated as "electrically operated switch mechanism," is shown and described in United States Patent No. 2,164,822, granted July 4, 1939, to Arthur G. Kershaw and Norman G. Kershaw.

The invention is illustrated by way of example in the accompanying drawing of which Figure 1 is a diagrammatic representation of a stretch of railway track comprising a number of routes. Figure 1 also shows typical operating and indication circuits for one of the switches in the stretch of railway track, and shows energizing circuits for a signal for one of the routes. Figure 2 is a diagram of connections illustrating in conventional form the control of the signal for one of the routes shown in Figure 1.

Figures 3 and 4 are diagrams similar to Figure 2, illustrating respectively the control of the approach locking release relay provided in accordance with the invention and the control of the route setting and locking relay for one of the routes with which the signal of Figures 1 and 2 is associated. Figure 4 also shows the control of the point or switch setting and locking relay for one of the track switches in the route with which the signal of Figures 1 and 2 is associated.

Figures 5 and 6 are views similar to Figures 2, 3 and 4 illustrating the invention as applied to a switch and signal lever control system.

Similar reference characters refer to similar parts in each of the several views.

In each of the views, the contacts operated by the various relays or other devices are identified by numbers, such numbers having distinguishing prefixes from which they are separated by a dash when the contacts are shown apart from the relay or other device by which they are operated. The prefix for each of these contact numbers comprises the reference character for the respective relay or other device by which they are operated. For example, contact $6KR-10$ shown in Figure 2 in the circuit for energizing relay IHR is identified by the number 10 separated by a dash from the prefix $6KR$ which is the reference character for relay $6KR$, shown in Figure 1, by which this contact is operated. Similarly, contact $\text{ILR}(\text{R})-14$, also shown in the energizing circuit for relay IHR in Figure 2, is identified by the number 14 separated by a dash from the prefix $\text{ILR}(\text{R})$ which is the reference character for the reverse solenoid $\text{ILR}(\text{R})$ of the route setting and locking relay ILR shown in Figure 4.

Referring now first to Figures 1 to 4 inclusive, it will be seen that a stretch of railway track is diagrammatically illustrated in Figure 1 as divided by insulated joints 2 into a number of successive track sections A, B, C, D, E. The sec-

tions B, C and D comprise track switches as indicated at 4, 5 and 6, forming part of a number of corresponding different routes which may be traversed by traffic leaving section A. Route No.

- 5 1, as indicated by the arrow $\text{R}1$, is assumed to include track sections B, C, D and E in that order so that for this through route switches 4, 5 and 6 must be in their normal settings. Routes Nos. 4, 5 and 6 will involve the setting 10 of switches 4, 5 or 6 respectively to their reverse positions and each route is provided with a route setting and locking relay of the kind above referred to which controls the setting of all the switches associated with the route, it being understood that each route may include other switches than those indicated at 4, 5, 6 by way of example.

Each of the track sections A, B, C and D is shown provided with a track circuit including a 20 suitable source of current, which may be a battery 3, connected across the rails adjacent one end of the section, and a track relay, designated by the reference character TR preceded by the reference character for the associated section, connected across the rails adjacent the opposite end of the section.

Signal IS may govern the movement of traffic over routes Nos. 4, 5 and 6, as well as over route 30 No. 1, or separate signals may be provided for each route or group of routes. In the specific example here considered Figure 2 illustrates the control of signal IS to control traffic over No. 1 route.

The route setting relay for No. 1 route is indicated at ILR in Figure 4, and is of the type above referred to, comprising a normal solenoid $\text{ILR}(\text{N})$ and a reverse solenoid $\text{ILR}(\text{R})$, the direct currents required for energizing these solenoids being derived from the output terminals of a rectifying 40 device LRJ , the input terminals of which are connected to the terminals ABX and ANX of a source of supply of alternating current.

The route setting relay ILR is arranged to be controlled by a manually operated lever or other control device indicated at ILRP in Figure 2 and having a normal position N and a reverse position R , and comprising a contact $\text{ILRP}-20$, shown in Figure 4, which is closed when the control device is in its normal position as indicated by the letter N adjacent the symbol for this contact (for setting the relay ILR to its normal position) and a contact $\text{ILRP}-25$ which is closed when the control device is in its reversed position, it being understood that in the normal position of a route setting and locking relay the route 55 is dissolved and is set up when the relay is in its reverse position.

The route setting and locking relay ILR in turn controls a switch setting and locking relay for each switch in its route. The control circuits 60 for switch setting relay 6WR are shown, for example, in Figure 4. Switch No. 6 is also included in route 6, and relay 6WR is therefore also controlled by route setting and locking relay 6LR .

The signal IS for route No. 1 is controlled by a signal relay IHR which causes the signal IS to give a "proceed" or "danger" indication according to whether the relay IHR is energized or de-energized. Signal IS may be of any suitable design, but as here shown is of the color light type, comprising a proceed lamp G and a stop lamp R . The signal relay IHR is arranged to be controlled by the manually operated control device ILRP which in its normal position inter-

rupts the energizing circuit of the relay IHR but when operated to its reverse position completes a circuit as shown in Figure 2 from one terminal BX of a source of current, through a contact 7 (closed when the control device ILRP is in its reverse position), contacts closed when switch indication relays 4KR , 5KR and 6KR are normally energized, front contacts $6\text{LR}(\text{N})-11$, $5\text{LR}(\text{N})-12$ and $4\text{LR}(\text{N})-13$ closed when the route setting relays 6LR , 5LR and 4LR respectively of other conflicting routes are in their normal positions, front contact $1\text{LR}(\text{R})-14$ closed when the route setting relay 1LR is in its reverse position, and the winding of relay IHR to the other terminal NX of the source of current. The switch indication relays are normally energized as controlled by pole changing contacts, such for example as contacts 15 and 16 operated by switch 6 for controlling relay 6KR shown in Figure 1, when the corresponding switches 4 , 5 and 6 occupy their normal positions for through traffic so that it will be evident that in order to energize the signal relay IHR to cause a "proceed" indication to be given when the control device ILRP is operated for this purpose, it is essential that the switches 4 , 5 and 6 should occupy their normal positions, that the route setting relays 6LR , 5LR and 4LR for conflicting routes should be in their normal or inoperative settings and that the route setting relay 1LR for the route No. 1 corresponding to signal IS should be in its reverse setting.

Referring now again to Figure 4, it will be seen that the energizing circuit of the normal solenoid $1\text{LR}(\text{N})$ of the route setting and locking relay 1LR includes, in addition to the contact $1\text{LRP}-20$, a back contact $1\text{HR}-19$ of the relay 1HR and a front contact $\text{ATR}-17$ of a track relay ATR which is energized when the approach section A is unoccupied by a train or vehicle. A parallel circuit to that including the front contact of relay ATR includes a front contact $1\text{ANS}-18$ of an approach locking release relay 1ANS . The energizing circuit for the reverse solenoid $1\text{LR}(\text{R})$ of the route setting relay 1LR includes, in addition to the contact $1\text{LRP}-25$, a series of contacts designated $1\text{R}(\text{N})-21$, $1\text{R}(\text{N})-22$, $1\text{R}(\text{N})-23$, and $1\text{R}(\text{N})-24$, each of which is closed only when the route setting and locking relay of a corresponding conflicting route is in its normal setting.

Referring now to Figure 3, which illustrates the energizing circuit for the approach locking release relay 1ANS for route No. 1, this relay is of the slow acting type and does not, when de-energized, move to its de-energized position until after the expiration of a predetermined interval of time.

The relay 1ANS is provided with a pick-up circuit passing from one terminal BX of a source of current, through contact $1\text{LR}(\text{R})-26$ closed only when the relay 1LR is in its reverse setting, a back contact $\text{BTR}-27$ of a track relay BTR which is de-energized when the track section B is occupied by a train or vehicle, and the winding of relay 1ANS to the other terminal NX of the source of current.

The relay 1ANS is also provided with a stick circuit including its own front contact 28 around the back contact of track relay BTR above referred to.

The operation of the system above described is as follows:—

Assuming that the route setting relay 1LR for route No. 1 is in its normal position, this route

may be set up by operating the control device ILRP to its reverse position so as to energize the solenoid $1\text{LR}(\text{R})$ of the relay 1LR . The normal solenoid $6\text{WR}(\text{N})$ of switch setting relay 6WR 5 will then become energized by its circuit passing from terminal BX , through contact $\text{DTR}-29$, contact 30 of solenoid $6\text{LR}(\text{N})$, contact 31 of solenoid $1\text{LR}(\text{R})$, and the normal solenoid winding $6\text{WR}(\text{N})$ of relay 6WR to terminal NX . The normal operating circuit for switch motor M will then become closed, causing switch 6 to be moved to the normal position if it has previously occupied the reverse position. This circuit passes from terminal BX , through contact $6\text{WR}(\text{N})-34$, normal field winding 35 of motor M , and armature 38 of motor M to terminal NX . Switches 4 and 5 will be controlled similarly to switch 6 by relay 1LR .

Under these conditions, the signal relay IHR 20 will be energized providing the track switches 4 , 5 and 6 are in or operate to their normal position. Proceed lamp G of signal IS will therefore be lighted by its circuit including the front point of contact $1\text{HR}-39$.

The approach locking release relay 1ANS was de-energized so long as the relay 1LR was in its normal position, but the pick-up circuit of the relay 1ANS is completed when relay 1LR is in its reverse position and a train or vehicle has entered track section B. When the relay 1ANS has been thus picked up, the relay is maintained energized through its stick circuit after the train or vehicle has left section B and so long as relay 1LR is in its reverse position.

The relay 1LR may, however, be restored to its normal position by the operation of the control device ILRP to energize the normal solenoid $1\text{LR}(\text{N})$ so long as the track section A is unoccupied and the signal relay IHR is de-energized.

So long, therefore, as the approach section A leading to the signal IS is unoccupied, the relay 1LR may be freely set from its reverse position to its normal position regardless of the position of the relay 1ANS , the stick circuit of this relay being, however, interrupted when the relay 1LR moves from its reverse position towards its normal position when the contact $1\text{LRP}-20$ is closed. Since, however, the relay 1ANS is slow-releasing, the interruption of its stick circuit does not at once cause the relay to assume its deenergized position in which the energizing circuit of the solenoid $1\text{LR}(\text{N})$ would be entirely interrupted to effect approach locking if the shunt circuit including the front contact of relay ATR were also broken due to the presence of a train or vehicle in track section A. Consequently, the circuit through the front contact of relay 1ANS is maintained for a period of time sufficiently long to permit the normal solenoid $1\text{LR}(\text{N})$ to be energized to set the relay 1LR to normal, it being understood that the completion of this circuit is only effected provided that the signal IS is giving a "danger" indication.

In describing more in detail the control of relay 1LR by relay 1ANS , I shall assume that the solenoid $1\text{LR}(\text{R})$ of relay 1LR has been energized, as previously described, by operation of the control device ILRP to its reverse position. I shall further assume that a train then enters track section B, causing relay 1ANS to become energized by its pick-up circuit previously traced, and that a following train enters section A, de-energizing relay ATR . The circuit previously traced for solenoid $1\text{LR}(\text{N})$ will therefore be open at contact $\text{ATR}-17$. The second or parallel cir-

cuit for solenoid 1LR(N) including contact 1ANS-18 can, however, now be closed if the control device 1LRP is returned to its normal position in which its contact 1LRP-20 is closed, and if relay 1HR closes its back contact 1HR-19 in response to this movement of control device 1LRP. With the back contact 1HR-19 also closed, signal 1S will indicate stop.

Solenoid 1LR(N), upon becoming energized, will open contact 1LR(R)-26 in the circuits for relay 1ANS which will thereby be deenergized. Relay 1ANS is, however, slow releasing, and therefore its contact 1ANS-18 will remain closed long enough for solenoid 1LR(N) to complete the operation of relay 1LR and close its contact 32 in the circuit for solenoid 6WR(R) which can be energized if solenoid 6LR(R) is then energized by operation of the corresponding route control device.

From the description in the Kershaw et al Patent No. 2,164,822 previously referred to, it follows that contact 32 of solenoid 1LR(N) will not open when this solenoid becomes deenergized, but will remain closed until solenoid 1LR(R) is again energized. Similarly, contacts of solenoid 1LR(R) will become closed when solenoid 1LR(R) becomes energized, and will remain closed until solenoid 1LR(N) becomes energized.

After the relay 1ANS has eventually assumed its de-energized position, the approach locking evidently cannot be released so long as relay ATR is de-energized, that is, so long as section A is occupied.

In order to effect the re-energization of the relay 1ANS, it is evidently necessary for the relay 1LR to be again set to its reverse position so as to close the front contact 1LR(R)-26 (Figure 3) and for the track section B to be again occupied so as to close the back contact BTR-27 of relay BTR.

It will thus be seen that when once the approach locking has been established by the de-energization of the relays ATR and 1ANS, this locking can only be again released by the setting of the relay 1LR to its reverse position and the passage of a train or vehicle into track section B. Furthermore, the de-energization and release of relay 1ANS due to current failure in either its pick-up or stick circuit will prevent the release of the approach locking, thus ensuring safety in operation under all conditions.

In Figures 5 and 6, the invention is illustrated as applied to a system in which the control of the switches and signals of a route is effected by corresponding point and signal levers in the well-known manner.

As shown in Figure 5, the energizing circuit of the signal relay 1HR for the signal 1S of route No. 1, includes signal lever contact 43, closed when the signal lever is moved to its reverse position, and contacts 42, 41, and 40 on the individual switch levers controlling track switches 6, 5 and 4, these contacts being closed only when the corresponding switch levers are all in their normal positions.

The control of the energizing circuit for the approach locking release relay 1ANS is effected by a contact indicated as 44 on the route or signal lever 1L, which is closed when this lever is in its reverse position and is maintained closed until the lever, when moved away from its reverse position towards its normal position, has cleared the locking mechanism controlled by the approach locking release relay 1ANS. This relay need thus not be slow-acting as it is not de-

energized until the route or signal lever has moved beyond the position at which the locking mechanism is operative to prevent its movement to normal.

5 As shown in Figure 6, a back locking mechanism K is arranged to be provided for the signal or route lever, the releasing coil 51 for this locking mechanism being energized through a circuit including a contact 50 of the lever, front contacts ATR-49 and 48 of relays ATR and 1ANS and a back contact 1HR-47 of the signal relay 1HR. A locking segment 54 is mechanically connected with lever 1L so that when lever 1L is moved to its reverse position, segment 54 moves 15 toward the right, and locking dog 52 drops down off of the projection 53 of segment 54. When lever 1L is returned toward its normal position, dog 52 in its lowered position will engage the projection 53, thereby arresting the movement 20 of lever 1L at its indication position B until the releasing coil 51 becomes energized and lifts dog 52 out of engagement with projection 53 of segment 54. The lever can thus only be restored to its normal position provided that the track section A is unoccupied or that the relay 1ANS is energized.

Lever 1L can be mechanically interlocked with switch levers 4L, 5L and 6L, as indicated by the dash line 57 in Figure 5, so that when lever 1L is moved to its reverse position R, levers 4L, 5L and 6L are locked in their normal positions and cannot be reversed until lever 1L has been returned past its indication position B. Switch setting relay 6WR can be controlled by lever 6L 35 and by track relay DTR as shown in Figure 6.

The invention is evidently not limited to the particular arrangements and connections above described and illustrated by way of example, which may be modified in various respects in 40 order to meet particular conditions.

Having now particularly described my invention, I declare that what I claim and desire to secure by Letters Patent is:

1. In a control system for a stretch of railway track including a track switch, including a signal controlled by a manual control device independently of occupancy of said stretch of track by a train for governing traffic movements over a route containing said track switch, and provided 45 with approach locking means for preventing an operation of said switch if an approach section for said signal is occupied by a train and if said manual control device has been put into condition for clearing said signal, the combination comprising a normally de-energized approach locking release relay, means controlled by said approach locking release relay when in the energized condition for nullifying said approach locking means, and means responsive to said manual control device if put in condition for clearing said signal and to occupancy of said stretch of track beyond said signal for energizing said approach locking release relay while said signal is in the clear condition.

2. In a control system for a stretch of railway track including a track switch, including a signal controlled by a manual control device independently of occupancy of said stretch of track by a train for governing traffic movements over a route containing said track switch in a given position, and including a route setting and locking relay comprising a normal solenoid which upon becoming energized effects a condition required for operation of said switch to the opposite position and also comprising a reverse sole-

noid which when energized effects a condition required for operation of said switch to said given position and said route setting and locking relay remaining locked in the position to which it was last set until its opposite solenoid is energized, the combination comprising a normally de-energized approach locking release relay, means responsive to said manual control device if put in condition for clearing said signal and responsive to occupancy of said route beyond said signal for energizing said approach locking release relay while said signal is in the clear condition, and a front contact of said approach locking release relay included in a circuit for energizing said normal solenoid in multiple with a contact which is closed only if an approach track section for said signal is unoccupied.

3. In a control system for a stretch of railway track including a track switch, including a signal controlled by a manual control device independently of occupancy of said stretch of track by a train for governing traffic movements over a route containing said track switch in a given position, and including a route setting and locking relay comprising a normal solenoid which upon becoming energized effects a condition required for operation of said switch to said given position and said route setting and locking relay remaining locked in the position to which it was last set until its opposite solenoid is energized, the combination comprising a normally de-energized approach locking release relay, a pick-up circuit for energizing said approach locking release relay closed by said route setting relay in the reverse position and by the occupied condition of said stretch of track beyond said signal, a stick circuit closed by said route setting relay in the reverse position for retaining said approach locking release relay energized, and a front contact of said approach locking release relay included in an energizing circuit for said normal solenoid in multiple with a contact which is closed only if an approach track section for said signal is unoccupied.

4. In a control system for a stretch of railway track including a track switch, including a signal controlled by a manual control device independently of occupancy of said stretch of track by a train for governing traffic movements over a route containing said track switch in a given position, and including a route setting and locking relay comprising a normal solenoid which upon becoming energized effects a condition required for operation of said switch to the opposite position and also comprising a reverse solenoid which when energized effects a condition required for operation of said switch to said given position and said route setting and locking relay remaining locked in the position to which it was last set until its opposite solenoid is energized, the combination comprising a normally de-energized slow release approach locking release relay, means responsive to said manual control device if put in condition for clearing said signal and responsive to the occupied condition of said route beyond said signal for energizing said approach locking release relay, and a front contact of said approach locking release relay included in an energizing circuit for said normal solenoid in multiple with a contact which is closed only if an approach track section for said signal is unoccupied.

5. In a control system for a stretch of railway track including a track switch and a signal for governing traffic movements over said switch, including mechanically interlocked levers for effecting operations of said switch and clearing said signal, including approach locking means for arresting movement of the signal lever at a given indication position if said signal lever is returned from a reverse position for clearing said signal toward a normal position while an approach section for said signal is occupied, the combination comprising an approach locking release relay, a contact operated by said signal lever closed while said signal lever is in its said reverse or said indication position or in any other position between these two positions, means effective while said signal is in the clear condition for energizing said approach locking release relay including said contact of said signal lever and controlled by the occupied condition of said stretch of track ahead of said signal, and means comprising a front contact of said approach locking release relay for releasing said approach locking means.
- 25 6. In a control system for a stretch of railway track including a track switch and a signal for governing traffic movements over said switch, including mechanically interlocked levers for effecting operations of said switch and clearing said signal, including an electric lock which when de-energized arrests movement of the signal lever at a given indication point when said lever is being returned to a normal position from a reverse position to which it has been moved for clearing said signal, the combination comprising an approach locking release relay, a pick-up circuit controlled by said signal lever when operated to said reverse position and by the occupied condition of said stretch of track beyond said signal for energizing said approach locking release relay, a stick circuit independent of track occupancy controlled by said signal lever for retaining said approach locking release relay energized until said signal lever is moved beyond said given indication point toward its normal position, and a circuit including a front contact of said approach locking release relay in multiple with a contact which is closed only if an approach section for said signal is unoccupied for energizing said electric lock.
- 40 7. In a control system for a stretch of railway track capable of arrangement into a plurality of routes and having signal means for governing traffic movements over each of said routes, including manually controllable route means for arranging each of said routes, and including approach locking means for retaining each route as arranged by the corresponding manually controllable route means if an approach track section for its signal means is occupied by a train, the combination comprising a normally de-energized approach locking release device for a given route, a circuit for energizing said approach locking release device while said signal is in the clear condition closed at one point by the route control means for said given route when in condition for arranging said given route and closed at another point by a contact which is closed when said given route is occupied by a train, and means comprising said approach locking release device in its energized condition for nullifying the approach locking means for said given route.
- 45 8. In a control system for a stretch of railway track including track switching means for arranging a plurality of routes over said stretch,
- 50
- 55
- 60
- 65
- 70
- 75

including manually controllable means for effecting operation of said track switching means for arranging each of said routes, and including approach locking means for rendering said manually controllable means ineffective to operate said switching means for each route if an approach track section for the corresponding route is occupied by a train, the combination comprising a normally de-energized approach locking release device for a given route, a circuit for energizing said approach locking release device closed by said manually controllable means when in con-

dition for effecting arrangement of said given route and by a contact which is closed if said given route is occupied by a train, a stick circuit controlled by said manually controllable means for retaining said approach locking release device energized while said signal is in the clear condition, and means controlled by said approach locking release device in the energized condition for nullifying the approach locking means for 5 said given route.

CHARLES FRANCIS DICKSON VENNING.
